UNITED STATES PATENT OFFICE.

GEORGE ROGERS FAGAN, OF PHILADELPHIA, PENNSYLVANIA.

DESIGN FOR ORNAMENTATION.

Specification forming part of Design No. 6,488, dated March 4, 1873.

To all whom it may concern:

Be it known that I, GEORGE ROGERS FAGAN, of Philadelphia, Pennsylvania, have invented a Design for Ornamentation, of which the following is a specification:

The design is fully represented in the accompanying photographic illustration, to which reference is made; and consists of a piece of material cast or wrought so as to represent a group or pile of coins lying superposed upon each other. The design may be made to represent gold, silver, or copper coins of the United States, or any foreign nation or nations, the essential feature of the design being

the group or pile of coin. This design is intended to be affixed upon paper-weights, jars, or as an ornament upon furniture, and generally as a means of ornamentation.

Claim.

What I claim as my invention is—

As a design for ornamentation, a configuration representing a group of coins, substantially as shown and described.

GEORGE ROGERS FAGAN.
